HOLDER FOR PHONOGRAPH RECORD JACKETS

Richard D. Gamble, 8910 Wonderland Ave.,
Los Angeles, Calif.

Filed May 6, 1963, Ser. No. 74,763

Term of patent 14 years

(Cl. D33—3)

FIG. 1 is a perspective view of a holder for phonograph record jackets showing my new design; and

FIG. 2 is a similar view wherein the jacket holding arms are provided with squared ends and wherein an upper cap element is connected to the support pole by a rod of reduced diameter.

The dominant features of my design reside in the portions shown in full lines.

I claim:

The ornamental design for a holder for phonograph record jackets, substantially as shown and described.
